UNITED STATES PATENT OFFICE

JOHN H. DOMKEE, OF WEST HAVEN, CONNECTICUT, ASSIGNOR TO THE WIRE NOVELTY MANUFACTURING COMPANY, OF WEST HAVEN, CONNECTICUT, A CORPORATION OF CONNECTICUT

BUTTON LOOP

Application filed August 19, 1931. Serial No. 558,032.

This invention relates to button loops and more especially to that type of button loops made from a piece of wire the extremities of which are connected by a clip coupling permitting therein limited relative movements of the extremities upon the lateral expansion and contraction of the button loop.

The art contains numerous forms of connecting members that permit the functioning therein of the button loop extremities, but there is still a demand for an improved connecting member that, from the view-point of manufacture and appearance, will be inexpensive and neat. It is old in the art to provide outwardly bent and relatively abutting tips of aligned extremities of a button loop, and the art also discloses connecting members adapted to be mounted upon such formed extremities by means, for instance, of sleeves connected by flat arcuate portions covering the ends of the wire and forming a depressed part for the reception of the shank of a button, the walls of the flat arcuate portions being parallel one to the other by reason of the fact that the connecting member is folded in the middle so that portions equal one to the other in size and form depend in saddle-like fashion from either face of the button loop. The improved connecting member, about to be explained, however is a unique formation of a single piece of sheet metal providing sleeves having connecting portions covering outwardly bent and relatively abutting tips of aligned extremities of the button loop upon which the sleeves are loosely mounted and providing a seat for the shank of a button, the formation including a single depending display portion with curved outline and off-set into the middle of the plane of the button loop below the abutting tips. Therefore the objects of the invention are to provide a simple and inexpensive button loop of the expandable type; to provide for a button loop having outwardly bent and relatively abutting tips of aligned extremities, a connecting member enclosing said extremities and tips and providing a single depending display portion below said tips; and to provide for such a button loop a connecting member having a seat for the shank of a button, and a single depending

portion of which a curved marginal part extends slightly below the periphery of a seated button. With these and other objects in view as may become apparent from the within disclosures, the invention consists not only of the particular form herein pointed out and illustrated in the drawings, but readily admits of certain modification within the scope of what hereinafter may be claimed.

To best understand the character of the invention, reference is made to one illustrative device embodying the invention and illustrated by the accompanying drawings in which the Figure 1 is an upright face elevation of a button loop and connecting member, illustrating in dotted line the extremities in substantially abutting normal positions within the member; the Figure 2 is an edge view of the device; the Figure 3 is an upright face elevation of the laterally expanded device; the Figure 4 is an elevation of the connecting member in template form; and the Figure 5 is a perspective view of the formed connecting member.

Referring more particularly to the drawings, the button loop is formed in a manner well-known to the art to provide the suspension loop 1 having the horizontal bar 2 around which a looped strap (not illustrated) may be placed that the button loop may be suspended therefrom, the spring arms 3 and 4 cooperating to provide the button-receiving loop 5 and the button-retaining loop 6 having the intermediate restricted throat portion 7, the extremities 8 and 9 being bent into relative alignment, one with the other, and the enlargement or tips 10 and 11, of the extremities 8 and 9, being bent outwardly and substantially abutting, one against the other. Such structure in itself is old, and the essence of this invention comprises the novel manner by which the extremities 8 and 9 are connected. The improved clip coupling or connecting member 20 is stamped out of sheet metal in substantially the template form, illustrated by the Figure 4, having the sleeves 21 relatively spaced by the connecting portions 22 and 23, the member 20 being provided with the perforation 24 substantially separating the connecting portions 22 and 23 and the de-

pending portion 25 out of which the connecting portion 22 is cut, as at 26, the portion 25 having the curved edge 27. The member 20 is folded over the aligned extremities 8 and 9 so that the perforation 24 provides a seat for the shank S of a button within the button-retaining loop 6, each sleeve 21 is then formed loosely around an aligned extremity 8 or 9, leaving the connecting portions 22 and 23 in substantially parallel planes upon opposite sides of the extremities 8 and 9, the engagement of the connecting portions 22 and 23 with the tips 10 and 11 maintaining the member 20 against rotation upon the aligned extremities 8 and 9, and substantially concealing the tips 10 and 11 from view. In the formation of the sleeves 21, the depending portion 25 is offset to the middle of the plane of the button loop, as best illustrated by the Figures 2 and 5, the cut 26 being sufficient to permit the connecting portion 22 to remain undisturbed in its parallel relation to the connecting portion 23.

In use, the shank S may be urged from the position within the button loop, illustrated in full line by the Figure 1, to the position illustrated by the Figure 3, thus laterally expanding the button loop to permit the shank S to pass into and through the throat portion 7 to assume the seated position within the button-retaining loop 6 as illustrated in dotted line by the Figure 1 wherein a marginal part of the depending portion 25 is shown to extend below the dotted periphery 12 of a seated button. The button loop with the improved connecting member provides a reversible device in that the elevation opposite to that illustrated by the Figure 1 is substantially identical therewith.

40 I claim:

1. A button loop having relatively aligned extremities provided with enlargements, and a clip coupling formed from a single piece of sheet-metal and mounted upon the aligned extremities, the clip coupling having spaced parallel cut-edged portions substantially enclosing the enlargements, and a depending display portion off-set below the enlargements, and free from both spaced parallel portions, to the middle of the plane of the button loop.

55 2. A button loop having relatively aligned extremities provided with enlargements, and a clip coupling having spaced sleeves loosely surrounding outer portions of the extremities, the sleeves being connected by spaced parallel portions substantially enclosing the enlargements, and a depending display portion integral with the sleeves, but cut away from one of the spaced parallel portions, and off-set below the enlargements to the middle of the plane of the button loop.

60 3. A button loop having relatively aligned extremities with the tip of each extremity bent outwardly and substantially abutting

one against the other, and a clip coupling provided with a depressed seat for the shank of a button, the clip coupling being mounted upon the aligned extremities and having sleeves loosely surrounding outer portions of the extremities, the sleeves being connected by spaced parallel portions substantially enclosing the tips of the extremities; and a depending display portion integral with the sleeves but cut away from one of the spaced parallel portions and off-set, below the tips of the aligned extremities, to the middle of the plane of the button loop.

4. A clip coupling adapted to connect, for a limited movement therein, enlargements of aligned extremities of a wire formation, the clip coupling comprising a sheet-metal saddle-like formation adapted to be placed over aligned extremities and providing spaced means for securing the clip coupling upon the aligned extremities, spaced parallel portions adapted to substantially enclose the enlargements, and a rigid depending display portion integral with the securing means, but free from both spaced parallel portions, the depending portion being off-set below the spaced parallel portions into a plane midway of the spaced parallel portions.
